DESIGN FOR A PENCIL SHARPENER

Ladd W. Hoffman, Los Angeles, Calif.

Application September 17, 1945, Serial No. 122,120

Term of patent 14 years

(Cl. D74—1)

To all whom it may concern:

Be it known that I, Ladd W. Hoffman, a citizen of the United States, residing at Los Angeles, in the county of Los Angeles and state of California, have invented a new, original, and ornamental Design for a Pencil Sharpener, of which the following is a specification, reference being had to the accompanying drawing forming part thereof.

Figure 1 is a perspective view of a pencil sharpener showing my new design;

Figure 2 is a side elevation of the sharpener; and

Figure 3 is a top plan view of the sharpener.

I claim:

The ornamental design for a pencil sharpener, substantially as shown.

LADD W. HOFFMAN.
